(57) **CLAIM**

The ornamental design for a footrest, as shown and described.

DESCRIPTION

FIG. 1 is a front, top, right-side perspective view of a second embodiment of a footrest;

FIG. 2 is a rear, bottom, left-side perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines in the drawings depict portions of the footrest that form no part of the claimed design.

1 Claim, 6 Drawing Sheets
